UNITED STATES PATENT OFFICE.

RANDOLPH L. WRIGHT, OF WEDGEFIELD, SOUTH CAROLINA.

COTTON-PACKER.

1,148,067.

Specification of Letters Patent. Patented July 27, 1915.

Application filed July 24, 1914. Serial No. 852,883.

To all whom it may concern:

Be it known that I, RANDOLPH L. WRIGHT, a citizen of the United States of America, and resident of Wedgefield, in the county of 5 Sumter and State of South Carolina, have invented certain new and useful Improvements in Cotton-Packers, of which the following is a specification.

This invention relates to presses and particularly to cotton baling machines.

An object of this invention is to provide means for tamping cotton lint so as to compress it in the presser boxes of a baling machine, the said invention being designed to 15 accomplish the results which at the present time are accomplished by tramping on the cotton as it is delivered to the said molds or hoppers.

Furthermore, an object of the present invention is to provide novel means for tamping the lint as it is delivered to the presser boxes, thus causing a slight compression of the particles of lint as they are delivered rather than to press the same after a bulk 25 of material has been delivered to the presser box, it having been found that the continuous tamping operation, due to the jarring action and the weight of the compressing member so condenses the lint as to enable the 30 production of relatively heavy bales, as compared with their size and since this is accomplished by mechanical means of novel construction, the rapidity of action and the efficiency of action is very marked as compared with methods now in common use.

A still further object of this invention is to provide a tamping machine having novel means for elevating the tamping member, novel means being also provided for releasing the said tamping member and a still further object of the invention is to provide 40 novel means for oscillating a guide or frame for the tamping member to change the position of its stroke or the rotation of the stroke 45 upon each elevation or descent of the said tamping member.

A still further object of this invention is to provide means for holding the tamping member inactive while the molds or boxes 50 are being removed or replaced, and the said invention furthermore contemplates the provision of novel means for tripping the said tamping member so that it may be released from its elevating means and permitted to 55 fall by gravity.

A still further object of this invention is

to provide means for operating the oscillating means and the tamper elevating means from the power usually present in cotton gins so that the apparatus may be 60 operated or utilized economically and without auxiliary power.

With the foregoing and other objects in view, the invention consists in the details of construction, and in the arrangement and 65 combination of parts to be hereinafter more fully set forth and claimed.

In describing the invention in detail, reference will be had to the accompanying drawings forming part of this specification 70 wherein like characters denote corresponding parts in the several views, and in which—

Figure 1 illustrates a view in end elevation of the cotton tamper embodying the invention; Fig. 2 illustrates a side elevation 75 thereof; Fig. 3 illustrates a sectional view on the line 3—3 of Fig. 2; Fig. 4 illustrates an enlarged detail view of the tamper and the wheel for elevating the same; Fig. 5 illustrates a top plan view of the tamper 80 and the elevating wheel; Fig. 6 illustrates a detail sectional view of a fragment of the tamper and one of the guides; Fig. 7 illustrates a face view of the cam; Fig. 8 illustrates a sectional view of the cam on the 85 line 8—8 of Fig. 7; Fig. 9 illustrates an enlarged detail view of the pitman with the roller adapted to work in the cam groove; and Fig. 10 illustrates an enlarged detail view of the latch for holding the tamper 90 elevated.

In these drawings 15 denotes a suitable frame including the uprights 16 and 17, near the upper ends of each are the pintles 18 on which the guides 19 are oscillatingly 95 mounted. The guides may be of any construction but are here shown as consisting of bars of material having grooves 20 which receive the tongues 21 extending longitudinally in the edges of the tamper 22, thus the 100 said tamper is guided vertically and is carried from side to side as the guides are oscillated. The guides 19 are connected by a yoke 23 which yoke terminates in an arm 24. A link 25 is pivoted to the arm 24 and said 105 link carries a roller 25^a mounted on a pin 25^b and said roller enters the cam slot 26 in the cam wheel 27, which cam wheel 27 is secured to a power shaft 28 such as is employed under the floors of gins as they are 110 commonly constructed. The rotation of the cam wheel, therefore, oscillates the guides

and causes the tamper 22 to descend into the presser boxes 29 near the side walls thereof, that is to say, it descends near the side wall at one operation and at the opposite side wall 5 at the next operation and thereby compresses or condenses the lint uniformly throughout the area of the said presser box 29.

The tamper 22 is preferably of metal and has at one side a series of ribs 30 which ribs 10 may be integral with the tamper or they may be rods inserted or secured to the tamper in any appropriate way. As a means for elevating the tamper, a wheel 31 is mounted on a shaft 32, the said shaft 32 having a 15 pulley 33 with a belt 34. The belt is driven from the power shaft of the gin through any type of power transmitting means, those shown in the drawings being sufficient for the purpose of illustrating one embodiment 20 of the invention, it being obvious that the power transmitting means may be modified to suit particular requirements. The wheel 31 is seen to have a series of teeth 35 which project between the ribs 30 and on the upward movement of the said teeth, they engage the ribs and communicate motion to the tamper. The shaft 32 is journaled in a swinging frame 36, the said frame having its upper end pivoted to the stationary frame 30 and being oscillatable with relation to the said stationary frame and with relation to the tamper, so that when the oscillating or swinging frame is moved away from the tamper, the teeth of the wheel 31 are disengaged from the ribs of the tamper, thus permitting the said tamper to descend by gravity and tamp the contents of the presser boxes. The swinging frame has a handle 37 by which the frame may move away from or 40 toward the tamper and provision is also made for oscillatingly swinging the frame automatically by a cam 38 which is carried by the tamper and contacts with the said frame as the tamper is elevated, thus 45 causing the said cam to force the swinging frame away from the tamper to such an extent as to disengage the teeth of the wheel from the ribs of the tamper. This operation will cause a release of the tamper and permit 50 it to descend by gravity in the same manner as the device would operate should the swinging frame be manipulated by hand.

Provision is made for holding the tamper in an elevated position when it is desired 55 to change the boxes or presser boxes and to this end the upper end of the tamper has a lug 39 adapted to enter a clamp or clasp 40 suspended from the frame. The clasp 40 consists of two coacting jaws pivoted so 60 that they approach each other or recede, the

object of the invention being that these jaws shall operate to engage the lug for holding the tamper elevated or that they may be forced apart by the lever 41 to release the lug and consequently the tamper, when assumption of the operation is to be had. The lever for operating the clips or clasps is actuated by a rod extending near the floor where it may be grasped by an operator. The lower ends of the tamper guides are 70 slotted to receive the plates 42 and the said plates 42 constitute brackets held by the uprights 16 and 17. As the guides oscillate, their lower ends are guided by the brackets. 75

As the functions of the several elements 75 of the device have been described in connection with a disclosure of the elements themselves, a detailed description of the operation will, it is thought, be unnecessary.

I claim—

1. In a cotton lint tamper, a frame, a guide oscillatingly supported thereby, a tamper adapted to reciprocate in the guides, means for elevating the tamper, and means whereby the elevating means is caused to release the tamper, and means for oscillating the guides. 80

2. In a cotton lint tamper, a frame, guides oscillatingly mounted on the frame, a tamper engaged by the guides, means for elevating the tamper, means for causing a release of the tamper by the elevating means, whereby the tamper is allowed to fall by gravity, means for oscillating the guides, and means for holding the tamper inoperative. 85

3. In a cotton lint tamper, a frame, guides oscillatingly mounted on the frame, a tamper engaged by the guides, means for elevating the tamper, means for causing the release of the tamper by the elevating means 100 whereby the tamper is allowed to fall by gravity, means for oscillating the guides, means for holding the tamper in inoperative position, and means for releasing the tamper from the last mentioned holding means. 105

4. In a cotton lint tamper, a frame, a tamper, oscillating guides for the tamper, means for oscillating the guide, a swinging frame, a tamper elevating wheel carried by the frame, means for rotating the elevating means, and means for swinging the frame away from the tamper whereby the tamper elevating wheel releases the tamper. 110

In testimony whereof, I affix my signature in the presence of two witnesses.

RANDOLPH L. WRIGHT.
